UNITED STATES PATENT OFFICE.

HERBERT JUBE GWYER, OF YONKERS, NEW YORK.

REFRIGERATOR CONSTRUCTION.

1,398,964.

Specification of Letters Patent.

Patented Dec. 6, 1921.

Application filed August 11, 1920. Serial No. 402,807.

To all whom it may concern:

Be it known that I, HERBERT J. GWYER, a citizen of the United States of America, residing at Yonkers, Westchester county,

5 New York, have invented a new and useful Refrigerator Construction, of which the following is a specification.

My invention relates to a refrigerator construction.

10 It is an object of my invention to provide a refrigerator cabinet which can be made in knock-down parts which may be easily assembled in cabinet formation.

15 It is a further object to provide a construction in which the four sides and the top and bottom may each be made and assembled in the shop as units and the units afterward secured together in cabinet formation by securing opposite sides to each 20 other.

And in general, the object is to provide a very strong, durable and efficient refrigerator which may be cheaply manufactured.

My invention in its preferred form comprises four side units, a top and bottom unit, 25 all of which parts after assembly are secured and held together in cabinet formation by simple means passing between opposite side units.

30 In the drawings are shown merely preferred forms of my invention.

Figure 1 is a front elevation of a refrigerator showing the parts held together by means securing the ends of the refrigerator 35 to each other.

Fig. 2 is a section taken substantially in the plane of the line 2—2 of Fig. 1.

Fig. 3 is an inside elevation of one end of the cabinet shown in Fig. 1.

40 Fig. 4 is a fragmentary view of the front unit shown in Fig. 1.

Fig. 5 is a perspective view of one corner of the front unit shown in Fig. 4.

45 Fig. 6 is a bottom plan view of the top unit shown in Fig. 1, and showing the securing rods in place.

Fig. 7 is a fragmentary sectional view of the upper end of the cabinet shown in Fig. 1.

50 Fig. 8 is a perspective view of one of the framing pieces of the top.

Fig. 9 is a front elevation of a modified form of cabinet in which the units are held together by means passing from the front to the back units.

Fig. 10 is a section taken substantially in 55 the plane of the line 10—10 of Fig. 9.

Fig. 11 is a fragmentary inside elevation of the front unit shown in Fig. 9.

Fig. 12 is a fragmentary view of the form of cabinet shown in Fig. 9 having front 60 removed.

Fig. 13 is a detail perspective of a front corner post showing a fillet member abutment for a door.

Referring now particularly to Figs. 1 to 65 8, 5—5 designate the two end units as a whole.

Each of the ends preferably comprises 70 corner posts 6—7 and upper and lower framing pieces 8—9. These posts and framing pieces may be mitered and secured together in any suitable manner as by means of the corner fastenings 10—10. The posts and framing members, constituting the end frame, are of substantially the same cross 75 section and in the preferred form are substantially of the section shown in Fig. 8. As shown in said figure there is provided in one side of the post a relatively wide groove 11. Extending within the member, preferably from the same side, is an aperture or relatively deeper groove 12. Upon another side may be provided spaced grooves 13—14, and the inner corner may be rabbeted or cut away as at 15. The two end units are pref- 80 erably duplicates of each other.

The front unit comprises a frame made up of frame members such as 16—17. Secured between two of the frame members of the front unit there may be a horizontal 90 cross beam 18 and a vertical beam 19 may be secured between another frame member and the cross beam 18. The frame members, such as 16—17, are each preferably provided with upstanding tongues or projections 20 95 for interfitting with the grooves in the end and top and bottom units.

If desired, part of the front unit frame may be slightly inclined or beveled as at 21 and the grooves 11 in the side unit may 100

be correspondingly beveled for the purpose of more securely clamping or holding the parts together.

The front panel unit frame in the form 5 shown is arranged to be substantially filled by doors and the inner part of the frame and beams are provided with ledges such as 22, which act as abutments or jambs for the doors.

10 The top unit preferably comprises two framing pieces 24—25, and two tie beams or end members 26—27. The framing pieces 24—25 are preferably of the same cross section as the members constituting the frame 15 of the end units and the description thereof given will suffice for a description of them. The framing pieces 24—25 are preferably provided with projections 28, and the tie beams 26—27 may have projecting tongues 20 or projections 29 flush with the projections 28.

The bottom unit is preferably made as a duplicate of the top and no separate description thereof is necessary.

25 The back unit may comprise a frame substantially similar to the frame constituting the front unit hereinbefore described. The back unit will also be provided with tongues or projections 30—30 for interengagement 30 with the grooves in the end units and the top and bottom units.

Suitable insulating panels may be secured 35 in the grooves provided for them in the ends, top, bottom and back units. It is, of course, obvious that if the front unit be not substantially filled by doors, then suitable insulating panels would likewise be provided in the front unit.

40 The parts are secured together in cabinet formation in the preferred form by means of bars or rods 31—31.

The parts may be assembled in cabinet formation in the following manner: One end unit is first positioned. The front unit may 45 next be engaged with the end and the projection 20 placed in the groove 12. The back unit may next be engaged with the end unit and the projection 30 in a similar manner placed in the proper groove in the back 50 corner post. The top and bottom members may next be engaged with the end and the projections or tongues 28 and 29 fitted into the grooves in the framing members 8—9. When the parts are thus far assembled the 55 last end unit is put in place with the respective tongues or projections of the aforementioned parts interfitted with the grooves in the last end in a manner similar to that just described for the first end unit. The 60 parts are now ready to be secured together.

The preferred means for securing the parts in cabinet formation are rods or bars passing transversely through one end unit, longitudinally through the grooves 12 in the

framing pieces of the top and bottom units, 65 and then through the opposite end unit. Suitable nuts and heads may be provided on the rods for drawing the end units together and securing all of the parts rigidly and securely together in cabinet formation. 70

In Figs. 9 to 12 I have shown a slightly modified form of my invention in which the parts are held together by means passing through and securing the front and back 75 units together to form the rigid cabinet construction. In this latter modification the front panel unit comprises corner posts 33—34 and upper and lower framing pieces 35—36. These members may be mitered at the corners and secured together by any suitable or desired means, such as the corner fastenings 37—37.

The corner posts and framing pieces are 80 preferably of the same cross section and in Fig. 13 I have shown a preferred form of section. This section is substantially the same as that described in connection with the first form of my invention. At one side of the post is a relatively wide groove 38 and there is provided an aperture 39 through 90 the post which in the preferred form is in the form of a deep groove extending below the groove 38. In another side of the post spaced apart grooves 40 are provided and the inside corner may be rabbeted or cut away 95 as at 41'.

In order to provide proper jambs or abutments for doors, suitable beams such as 41—42 may be provided between the posts and framing members. The front unit is provided with fillet members 44 fitting in the grooves 40 of the posts, framing members and beams. The fillets constitute in conjunction with the posts, jambs for the doors. 105

The back panel unit comprises corner posts 45—46 and framing pieces secured thereto in a manner similar to that described for the front unit. The back corner posts are preferably of the same cross section as 110 the front corner posts.

The side panel units each comprise frames 47—48. Projections, such as 49, are provided about the outside of the side frames for interfitting with grooves in front, back, top and bottom units. Suitable insulating panels 50—51—52 may be provided for the three sides and the top and bottom. It should be understood that should a different arrangement of doors be provided, that a part of the front unit may be provided with insulating panels to close the space not closed by doors. 115

The top and bottom units as shown particularly in Fig. 12, preferably comprise framing pieces 55—56 which are of substantially the same cross section as the posts and framing pieces hereinbefore de- 120

scribed. Suitable tie beams 57—58 secure the top and bottom framing pieces together and make up top and bottom frames. The members 55—56 may be provided with projections 59—60 and the tie members 57—58 may have longitudinal tongues or projections 61—62 abutting the projections 59—60, and substantially flush therewith.

It is of course understood that insulating panels may be provided in the top and bottom frames in a manner similar to that shown in Figs. 6 and 7.

Securing means shown in the form of rods 63 may be used to hold the parts together in cabinet formation.

To assemble the parts in cabinet formation, one of the sides, preferably the front, is first positioned. The end units are next put in place with the projections 49 on the frames fitting in the grooves 38 in the front unit. The top and bottom units may next be put in place with the projections 59—60 and the tongues 61—62 fitted in the grooves 38—38 in the top and bottom framing pieces. The back unit is next put in place with the projections and tongues on the sides, top and bottom units fitting in the grooves in the back unit in a manner similar to that described for the front unit.

In order to secure the parts together in cabinet formation, the rods 63 are passed transversely through apertures in the corners of the front unit, longitudinally through the apertures or grooves 39 in the top and bottom units and then transversely through apertures in the back unit. Heads and nuts may be provided on the rods for drawing the front and back units together and rigidly and securely holding all of the parts together in cabinet formation.

It will thus be seen that I have provided a knock-down refrigerator consisting of but few separate parts which may be very compactly stored for shipment and which may be quickly and easily put together in a very simple manner.

In the specification and claims I employ the term "sides" to designate broadly the front and back units as well as the sides or ends proper.

While I have shown and described in great detail preferred forms of my invention, I am aware that various modifications may be made and I do not wish to be limited except as required by the appended claims.

I claim:

1. In a device of the character described, two opposed side panel units including corner posts, top and bottom framing pieces secured to said corner posts, two side panel units and top and bottom panel units, engaging said first mentioned side units and rods passing transversely through said first

mentioned side units and through said top 65 and bottom units for securing the parts together in cabinet formation.

2. In a device of the character described, two side units including grooved corner posts, top and bottom framing pieces of the same cross-section as the corner posts secured to said corner posts, two side units and top and bottom units fitting in the grooves in said first mentioned side units and rods passing transversely through said first mentioned side units and through said top and bottom units for securing the parts together in cabinet formation.

3. In a device of the character described, two side units including corner posts, top and bottom framing pieces secured to said corner posts, a pair of side units engaging said first mentioned side units, top and bottom units each including two framing pieces having longitudinal apertures therethrough, said top and bottom units engaging all of said side units and rods passing transversely through said first mentioned side units and through said apertures in said top and bottom units for securing the parts together in cabinet formation.

4. In a device of the character described, two opposed side units each including corner posts having a relatively wide groove in one side and relatively smaller spaced apart grooves in another side, a pair of side units comprising frames having insulating panels therein, said frames having parts interfitting with said relatively wide grooves, top and bottom units including two framing pieces of substantially the same cross-section as said corner posts, said top and bottom units having parts interfitting with the grooves in the framing pieces of the first mentioned side units and rods passing through said first mentioned side units and said top and bottom units for securing the parts together.

5. In a device of the character described, two opposed side units including corner posts and top and bottom framing pieces mitered to said corner posts, grooves in said corner posts and framing pieces, a pair of side units comprising frames and insulating panels, top and bottom units each comprising a frame and insulating panels, said top and bottom units and said pair of side units engaging the grooves in said first mentioned side units and rods passing transversely through the corners of said first mentioned side units and through the frames of said top and bottom units, whereby the parts will be secured together in cabinet formation.

6. In a device of the character described, two side units each including corner posts and top and bottom framing pieces secured together to form a frame, said corner posts and said framing pieces being of substantially the same cross-section and each having

1 a relatively wide groove in one side and a
2 relatively narrow deep groove in the bottom
3 of said wide groove, spaced apart grooves in
4 another side of said members, side units in-
5 cluding frames having parts for engagement
6 with the grooves in said corner posts, top and
7 bottom units having a pair of framing pieces
8 of the same cross section as said corner posts,
9 said top and bottom units engaging said side
10 units aforesaid and rods passing transversely
11 through the corners of opposite side units
12 and through the relatively narrow deep
13 grooves in said top and bottom framing
14 pieces whereby the parts will be held to-
15 gether in cabinet formation.

7. In a device of the character described,
two opposed side units, a second pair of side

units engaging said first mentioned side
units, top and bottom units including fram-
ing pieces and tie beams, said top and bottom 20
units each having tongues and projections
thereon for engagement with two of said side
units and means engaging opposite side units
for securing all of said parts together in
cabinet formation.

8. In a device of the character described,
two opposed side panel units, a second pair 25
of side units and top and bottom units each
engaging said first mentioned side units and
means co-operating with two of said side 30
units for securing all of the parts together
in cabinet formation.

HERBERT JUBE GWYER.
